UNITED STATES PATENT OFFICE.

JOHN J. HENNESSEY AND PETER N. MOORE, OF MILWAUKEE, WISCONSIN, ASSIGNEES OF ONE-HALF TO SAID HENNESSEY AND ONE-HALF TO WILLIAM H. MINER, OF CHICAGO, ILLINOIS.

FRICITION SPRING DRAFT-RIGGING FOR RAILWAY-CARS.

No. 862,910.

Specification of Letters Patent.

Patented Aug. 13, 1907.

Application filed April 26, 1907. Serial No. 370,190.

To all whom it may concern:

Be it known that we, JOHN J. HENNESSEY and PETER N. MOORE, citizens of the United States, residing in Milwaukee, in the county of Milwaukee and State of Wisconsin, have invented a new and useful Improvement in Friction Spring Draft-Rigging for Railway-Cars, of which the following is a specification.

Our invention relates to improvements in friction spring draft rigging for railway cars.

10 Our invention consists in the novel construction of parts and devices and in the novel combinations of parts and devices herein shown and described.

In the accompanying drawings, forming a part of this specification, Figure 1 is a side elevation, partly in vertical section, of a friction spring draft rigging embodying our invention; Fig. 2 is a plan view, partly in horizontal section; Fig. 3 is a vertical cross section on line 3-3 of Fig. 1. Fig. 4 is a detail perspective view of one of the friction blocks. Fig. 5 is a detail perspective 20 view of the other friction block, and Fig. 6 is a detail perspective view of the removable filler block.

In the drawing A A represent center sills or other longitudinal frame members of the car to which the draft rigging is applied, and A¹ the front or cross sill.

25 B is the draw-bar and B¹ the draw-bar extension, strap or yoke secured to the draw-bar in the usual manner.

C¹ are front and rear stops secured to the center sills or other longitudinal frame members of the car.

30 D is a longitudinally arranged direct acting spring in line with the draw bar and abutting at one end against the front follower E; and D¹ is a transversely arranged spring abutting at one end against the upright side wall f of the longitudinally movable friction box or shell F.

35 The rear end of the movable friction box or shell F may serve as the rear follower and engage the rear stops C¹ under buffing strains and the rear end of the draw bar strap B¹ under pulling strains.

The friction box or shell F has an internal longitudinal friction face f¹ parallel to the line of draft, and it may have integrally but preferably in a separate piece a transverse friction face f², preferably slightly wedging or inclined at a small angle to a line at right angles to the draw bar, and preferably formed by a readily removable filler block f³, placed in the rear end of the friction box of shell F.

40 G and G¹ are sliding friction blocks within the friction box or shell F. The friction block G is longitudinally movable with the draw bar, and is acted upon directly by the longitudinal spring D, and is furnished with a recess g to receive the rear end of said spring D. This longitudinally movable friction block G has a longitudinally extending friction face g¹, in sliding friction

55 tional engagement with the longitudinally extending friction face f¹ of the friction box or shell F.

The transversely movable friction block G¹ has a transversely extending and preferably slightly wedging or inclined friction face g² in sliding frictional engagement with the transversely extending friction face f² of the filler block f³ at the rear end of the friction box 60 or shell F. And this transversely movable friction block G¹ is furnished with a recess or socket g³ to receive one end of the transverse spring D¹.

The friction blocks G G¹ have inclined or wedging meeting faces g⁴ g⁵ in sliding frictional engagement with 65 each other. The inclined or wedging meeting faces g⁴ g⁵ of the longitudinally and transversely movable friction blocks G G¹ are preferably furnished with steps or offsets g⁶ g⁷, so that these inclined or wedging meeting faces are sectional, or extend in part in two different 70 planes parallel to each other, instead of extending continuously in one plane. The angle of the meeting faces g⁴ g⁵ is preferably about 60°, so as to give a greater transverse frictional sliding movement to the block G¹ than longitudinal movement to the block G, as the longitudinal movement of the block G, is, necessarily, limited to about the two and one-half inches permitted to the draw bar, although this angle may be varied as desired. The incline of the transverse friction face f² is 75 preferably about as indicated in the drawing, although this also may be varied as desired. By slightly increasing the incline or wedging action of the transverse friction face f² the resisting power of the draft rigging as a whole may be increased to any extent desired or required. As each of the friction blocks is directly 80 acted upon by one of the springs in the direction of its movement, the draft rigging, though exerting a powerful frictional resistance, will always act smoothly, uniformly, certainly and regularly, both in compressing and releasing, and without tendency to sticking or to 85 violent recoil.

H is the tie plate, having a longitudinal channel or guide h for the lower member of the draw bar strap or yoke B¹, and by which the draft rigging is supported. The inner upright faces of the center sills A A may serve 95 as guides or cheek plates to guide the longitudinally movable friction box or shell F, in cases where metal center sill are employed, as illustrated in the drawing, or where side plates or stop castings furnished with integral front and rear stops are not employed.

100 We claim:

1. In a friction spring draft rigging, the combination with the draw bar and draw bar strap or yoke, front and rear stops and a follower, of a longitudinally movable friction box or shell, having an interior longitudinal friction face and an interior transverse friction face, a longitudinally movable friction block having a longitudinal

JOHN J. HENNESSEY.
PETER N. MOORE.
